UNITED STATES PATENT OFFICE

ALBERT W. ENGEL, OF CHICAGO, ILLINOIS

TRANSPARENT ENVELOPE

Application filed December 26, 1931. Serial No. 583,273.

The purpose of this invention is to provide an improved package in the form of an envelope, employing transparent material such as "cellophane", and providing means for sealing the package without relying upon securing of one surface of the cellophane to another. The invention consists in certain features and elements of construction as herein shown and described, and as indicated in the claims.

In the drawing:

Figure 1 is a face view of an envelope embodying this invention.

Figure 2 is a rear elevation of the same showing the envelope sealed.

Figure 3 is a front elevation of the envelope with a portion broken out and showing the sealing flaps extended and unsecured.

Figure 4 is a detail section on a larger scale exaggerating the thickness of the materials and showing the flaps of the envelope and its liner partially folded, as in the process of sealing.

Figure 5 is a similar detail section showing the parts in fully sealed relation, being taken as a section at line 5—5 on Figure 2.

Figure 6 is a partial front elevation showing a modified form of securing means.

Figure 7 is a detail section taken as indicated at line 7—7 on Figure 6.

Figure 8 is a vertical medial sectional view of the liner.

The drawing illustrates this invention as a package designed to carry small articles of merchandise, such as gummed mounting corners of the general type shown in my Patent No. 852,018, and since these mounting corners are made in a variety of shapes, and sometimes in several different colors, it is an advantage to have a portion of the package transparent so that its contents may be seen readily without unsealing it. The envelope proper consists of a front wall, 1, folded over at its edges, 2, 2, formed in two sections, 3, 3, of the back wall, which are adhesively secured at 4 in a lap seam. The lower end is closed by a flap, 5, also adhesively sealed, and at the upper end there is provided a closure flap, 6, which is not gummed. To avoid the use of special gums

or sealing compounds the present invention undertakes to seal the flap, 6, without gumming the transparent material to itself.

Partly to solve the problem of sealing the flap, 6, and partly to provide an area suitable to receive printed descriptive matter relating to the contents of the package, I place in the transparent envelope a liner of light cardboard or other similar opaque material, having a front leaf, 7, and a back leaf, 8, integral with the front leaf, 7, and folded against it. The line of fold is indicated at 9, and extending upwardly from this line an opening, 10, is formed in the back leaf, 8. As shown, this opening is triangular in outline. When the package is filled with the gummed stickers or other material the contents are inserted between the leaves, 7 and 8, of the liner, so that a portion of said contents becomes visible through the transparent back wall, 3, of the envelope.

The rear leaf, 8, of the liner terminates substantially at the mouth of the transparent envelope, but the front leaf, 7, is longer and continues in three short sections defined by folds and indicated at 11, 12 and 13 on Figure 4. The section, 11, emerges from the mouth of the envelope under the flap, 6, and when these two parts are folded down against the back wall they may be secured by means of a gummed strip, 14, which is laid over the outer face of the flap 6. Since the corners of said flap, 6, are cut off diagonally, as indicated in Figure 3, the gummed under surface of the strip, 14, may be adhesively secured to the exposed triangular areas, 11^a, of the part, 11. The end portions of the strip, 14, are then bent at right angles to the plane of the flap, 6, and said flap, with the part, 11, disposed under it, is folded down flatly against the back of the envelope. The end portions, 14^a, are thus projected forwardly past the edges of the envelope.

The section, 12, of the liner, which is adjacent the section, 11, is now folded flatly against the back or outer surface of the flap, 6, and strip, 14, and the terminal section, 13, is folded over the top edge of the assembly and flatly against the front wall, 1, of the envelope.

envelope. The forwardly projecting end portions, 14^a, of the strip, 14, may then be pressed against the outer face of the section, 13, and adhesively secured thereto, as indicated in Figure 1. Thus the flap, 6, of the transparent envelope is locked between the sections, 11 and 12, of the liner member, or, more strictly, between the sealing strip, 14, and the section, 11, while these parts are held 10 in position by securement of the ends of the strip to the section, 13, at the front side of the envelope. The relative position of the parts is clearly indicated in the exaggerated sectional view of Figure 5.

15 If desired, suitable label material or other printed matter may be displayed on the exposed face of the section, 13, as indicated in Figure 1, and, likewise, on the exposed surface of the section, 12, as shown in Figure 2. As will be understood, this permits of conveniently printing the liner member as a single flat sheet before it is scored or creased for folding of the sections, 11, 12 and 13, about the flap, 6, of the envelope, since 25 both of the exposed faces of the leaves, 7 and 8, and the sides of the parts, 12 and 13, which will be exposed when the envelope is closed up, are all parts of the same surface of the liner member.

30 If desired, instead of employing the gummed strip, 14, for sealing the envelope, this part may be omitted and a pair of wire staples, 15, may be passed through the several folded flap sections, as shown in Figure 35, 6, and indicated in the exaggerated sectional view, Figure 7.

While there is shown and described herein certain specific structure embodying the invention, it will be manifest to those skilled 40 in the art that various modifications and rearrangements of the parts may be made without departing from the spirit and the scope of the invention, and that the same is not limited to the particular form herein 45 shown and described, except in so far as indicated by the appended claims.

I claim:

1. In combination with a transparent envelope, an opaque liner fitted therein, the 50 envelope having a flap, and the liner having a flap of three sections defined by transverse folds, the first section being folded down to extend from the mouth of the envelope under the flap thereof, the second section being 55 folded upwardly over the outside of said flap, and the third section being folded downwardly to lie against the opposite side of the envelope from that against which the first and second sections are disposed.

60 2. In combination with a transparent envelope, an opaque liner fitted therein, the envelope having a flap, and the liner having a flap composed of a plurality of sections embracing and enclosing the envelope flap, 65 and fastening means engaging one section

of the liner flap with another section thereof.

3. In combination with a transparent envelope as defined in claim 1, fastening means securing the said third section to one of the other sections of the flap of the liner. 70

4. In combination with a transparent envelope as defined in claim 2, the flap of the liner including a portion which extends from the envelope mouth under and then over the envelope flap, with means connected to said liner flap engaging the opposite face of the envelope at the same end thereof. 75

5. In combination with a transparent envelope, an opaque liner fitted therein, a portion of the envelope wall being folded over 80 a portion of said liner to interlock said parts with each other, and the liner having a flap composed of a plurality of sections defined by transverse folds, said sections being disposed to overlie both sides of the transparent envelope, and means securing one of said overlying sections to the other for sealing the envelope. 85

6. In combination with a transparent envelope, an opaque liner fitted therein and 90 formed with a sight opening or window to render visible a portion of the contents of the envelope, said liner including a flap composed of a plurality of sections extending 95 from the mouth of the transparent envelope and defined by transverse folds with one section overlying one side of the envelope and another section overlying the opposite side, and fastening means securing said sections together for sealing the envelope. 100

7. In combination with a transparent envelope, an opaque liner fitted therein and comprising two leaves united at a fold disposed in the bottom of the envelope, one leaf having one or more sight apertures to 105 render visible a portion of the contents of the envelope disposed between the leaves of the liner.

8. In combination with a transparent envelope, an opaque liner fitted therein and comprising two leaves united at a fold disposed in the bottom of the envelope, one leaf having one or more sight apertures to render visible a portion of the contents of the envelope disposed between the leaves of the liner, said liner having portions extending 110 from the mouth of the envelope and folded to overlie both sides of the envelope adjacent said mouth, together with means 115 securing said portions to each other in such overlying position. 120

9. In combination with a transparent envelope, an opaque liner fitted therein and comprising two leaves united at a fold disposed in the bottom of the envelope, one leaf having one or more sight apertures to render visible a portion of the contents of the envelope disposed between the leaves of the liner, said envelope having a flap, and one leaf of the liner having a flap composed of a 125 130

plurality of sections defined by transverse folds, said sections being disposed to overlie both sides of the transparent envelope, and means securing one of said overlying sections to the other for sealing the envelope.

10. In combination with a transparent envelope, an opaque liner fitted therein, the envelope having a flap, and the liner having a flap of three sections defined by transverse folds, the first section being folded down to extend from the mouth of the envelope under the flap thereof, the second section being folded upwardly over the outside of said flap, and the third section being folded downwardly to lie against the opposite side of the envelope from that against which the first and second sections are disposed, said liner being composed of two plies united at a fold disposed in the bottom of the envelope, 20 and one ply of said liner having a window to render a portion of the contents of the envelope visible through the transparent wall of the envelope.

11. The combination of an envelope and a liner therefor, comprising two leaves united at a fold which is disposed within the envelope at the side or end opposite its opening, one of said parts being of transparent material and the other part being of opaque 30 material, the part of opaque material having an aperture across which the transparent material extends to form a window which renders visible the contents of the envelope carried between the two leaves of the liner.

35. 12. The combination of an envelope and a liner therefor, comprising two leaves united at a fold disposed at the side or end of the envelope opposite its opening, one of said parts being of transparent material, and 40 the other part being of opaque material, the part of opaque material having an aperture extending adjacent the fold of the liner and the transparent material of the other part extending across said aperture to form a window which renders visible the contents of the envelope carried between the two leaves of the liner adjacent said fold.

45. In testimony whereof, I have hereunto set my hand at Chicago, Illinois, this 22nd day of December, 1931.

ALBERT W. ENGEL.
